BENJAMIN TREADWELL, OF BELLE PLAINE, SASKATCHEWAN, CANADA.

SCRAPER.

Specification of Letters Patent.

Patented Dec. 4, 1917.

1,248,953.

Application filed June 22, 1917. Serial No. 176,375.

To all whom it may concern:

Be it known that I, BENJAMIN TREADWELL, of the town of Belle Plaine, Province of Saskatchewan, and Dominion of Canada, 5 a subject of the King of Great Britain, have invented new and useful Improvements in Scrapers, and do hereby declare that the following is a clear and exact description.

This invention relates to improvements in 10 scrapers particularly adapted for use with disk plows. In the disk plows at present in use one of the drawbacks, which is very marked, is that the soil is inclined to adhere to the inner face of the disk, so that in 15 many cases greater tractive force is required to draw the plow, and one of the objects of the present invention is to overcome this difficulty and permit of the disk being at all times kept clean and free from any matter which will be inclined to adhere thereto.

Further objects are to render the scraper 20 capable of being automatically adjusted so that it will lie in close contact with the surface of the disk, to facilitate reversing 25 the scraper and thus keep the blade automatically sharpened, to readily adjust the scraper to any angle to suit any make or type of disk plow on which it is being used, and generally to adapt the several parts to better 30 perform the functions required of them.

With these and other objects in view, the invention consists essentially of the improved construction particularly described and set forth in the following specification 35 and accompanying drawings forming part of the same.

In the drawings,

Figure 1 is a perspective view of a disk showing the scraper arranged in position 40 relatively thereto.

Fig. 2 is a front elevation partly sectional showing the position of the scraper relatively to the disk.

Like characters of reference refer to like 45 parts in the several figures.

Referring to the drawings, A represents a rotatable disk of any usual description utilized on plows and the like above which extends a standard B which may form

60 part of a plow frame.

By reference to Fig. 1, it will be seen that the upper end of this standard is substantially channel shaped as shown at 10 and frictionally engages with the stub spindle 55 11, which is retained in position by bolts 12. The outer end of the stub spindle rotatably

engages with the sleeve 13 of a bracket which is provided with a downwardly extending lug 14, while adjacent to the end of the sleeve a second lug 15 is formed, the object of which will be made clear hereafter.

The sleeve 13 is designed to be secured in position by set screws 16, so that the said sleeve is capable of being rotated and adjusted to suit the requirements of the plow.

The lug 14 engages with the lug 17 and is pivotally attached thereto by the bolt 18, the outer end of the lug 17 having an integral sleeve 19, above which extends a cylindrical projection 20, which is arranged in substantially parallel relation to the longitudinal axis of the said sleeve.

The upper end of the cylindrical projection 20 is bifurcated and designed to pivotally engage with the end of the rod 21, the free end of which extends through the lug 15, the said rod being provided intermediate of its length with a collar or nut 22, between which and the lug 15, a spring is located.

This spring encircles the rod 21 and is adapted to press the projection 20 outwardly and hold it angularly disposed so that the scraper 24, which is carried by the sleeve 19, will be angularly disposed to the face of the disk A.

The scraper 24 consists of a flat plate 25, provided with a shank 26 which engages with a sleeve 19 and is provided with a plurality of orifices 27 through which cotter pins pass to hold the scraper in the desired position.

The assembly of the several parts will be readily understood from the foregoing description.

When a plow fitted with a scraper of this description is in use, the scraper is adjusted so that the bottom edge thereof is in intimate contact with the inner face of the disk A, and in the position the cotter pins are placed in the orifice 27 to hold the scraper in position. When the plow is in use, the spring 23 holds the scraper tightly against the face of the disk and all soil adhering to the said disk will be removed on contact with the said scraper.

When the scraper has been in use for some time so that the edge has become unduly worn on one side, the blade 25 may then be reversed by rotating the shank 26 in the sleeve 19 so that the opposite edge will then engage with the disk A and in

this manner the scraper is always automatically kept sharpened.

By providing the sleeve 13 with set screws 16, it will be understood that the scraper 5 may be adjusted so that it will engage with any part of the surface of the disk A and it also permits of the scraper being utilized on the several types of disk plows at present on the market.

10 From this description it will be seen that I have invented a scraper which can be advantageously utilized by farmers for keeping the disks of the plows clean during the operation of plowing, thereby reducing the resistance to traction of the plow and otherwise adapting it to more advantageously perform the functions which are required of it.

20 As many changes could be made in the above description and many apparently widely different embodiments of my invention within the scope of the claim constructed without departing from the spirit or scope thereof, it is intended that all matter contained in the

Copies of this patent may be obtained for five cents each, by addressing the "Commissioner of Patents, Washington, D. C."

accompanying specification and drawings 2 shall be interpreted as illustrative and not in a limited sense.

What I claim as my invention is:

A plow scraper of the class described, comprising a spindle, a sleeve mounted thereon, 30 means for securing the sleeve in position, an offset lug carried by the sleeve, extending therebeyond longitudinally thereof, a second lug carried by the sleeve, a second sleeve, a lug carried by the second sleeve pivotally 35 mounted to the first said lug, a projection on the second sleeve, adjustable resilient means intermediate of the projection and the second lug, and a scraper adjustably mounted in the second said sleeve, said offset lug permitting ready access to the adjusting means of the scraper.

In witness whereof I have hereunto set my hand in the presence of two witnesses.

BENJAMIN TREADWELL.
